UNITED STATES PATENT OFFICE.

JAMES J. BYERS, OF PENSACOLA, FLORIDA, ASSIGNOR TO EDD H. ROBERTSON, OF MOBILE, ALABAMA.

TUBE-EXPANDER.

SPECIFICATION forming part of Letters Patent No. 773,050, dated October 25, 1904.

Application filed February 6, 1904. Serial No. 192,395. (No model.)

To all whom it may concern:

Be it known that I, JAMES J. BYERS, a citizen of the United States, residing at Pensacola, in the county of Escambia and State of Florida, have invented new and useful Improvements in Tube-Expanders, of which the following is a specification.

My invention relates to new and useful improvements in tube-expanders; and its object is to provide a simple, durable, and compact device of this character which can be readily inserted and held within a tube and which has means whereby the expander can be easily rotated during the expanding operation.

A further object is to employ a device for tightening the expander within the tube.

With the above and other objects in view the invention consists of a tapered mandrel having a screw-threaded portion which is engaged by a hand-wheel revolvably mounted on a core to which is connected a handle. A ratchet is revolvably mounted upon the core and is adapted to be engaged by a pawl connected to an operating-handle. This ratchet is secured to the head of the tool, in which are located rollers adapted to bear at opposite sides upon the mandrel and upon the inner surface of the tube to be expanded.

The invention also consists in the further novel construction and combination of parts hereinafter more fully described and claimed, and illustrated in the accompanying drawings, showing the preferred form of my invention, and in which—

Figure 1 is a perspective view of the tube-expander. Fig. 2 is a horizontal section through the head thereof on line 2 2, Fig. 3. Fig. 3 is a central vertical section through the tool. Fig. 4 is a section on line 4 4, Fig.

Fig. 5 is a section on line 5 5, Fig. 3; and Fig. 6 is a section on line 6 6, Fig. 3.

Referring to the figures by numerals of reference, 1 is a tapered mandrel having a screw-threaded stem 2 extending from the small end thereof, and this stem extends through and is engaged by a hand-wheel 3, having a circular flange 4 on the inner face thereof and concentric therewith. This flange is revolvably mounted upon one end of a tubular core 5,

having a groove 6 adjacent one end for the reception of pins 7, which extend through the flange 4. An angular flange 8 is formed at the inner end of core 5 and is seated within the enlarged end 9 of a sleeve 10, which is revolvably mounted on the core 5. Balls 11 are interposed between flange 8 and the enlarged portion 9 of sleeve 10 and form an end bearing for the tool. A ring 12, having ratchet-teeth 13 thereon, is secured, by means of screws 14 or in any other suitable manner, to sleeve 10, and the head 15 of the lever 16 is loosely mounted on sleeve 10 and at opposite sides of the ring 12. A pawl 17 is pivoted within the head of the lever 16 and is held, by means of a spring 18, normally in engagement with the teeth 13 on ring 12. A collar 19 incloses and is secured to the core 5 at a point between sleeve 10 and flange 4, and a handle 20 extends from this collar. A cylindrical head 21 is located upon the flanged end 70 of core 5 and has an enlarged recessed end 22, which receives said flanged portion of the core and also the enlarged end 9 of sleeve 10. Screws 23 or other suitable fastening means are employed for securing the head to sleeve 75 10. A groove 24 is formed within the head near its inner end and receives pins 25, which project through a centering-ring 26, loosely mounted on the head and having ears 27 extending at right angles therefrom at desired 80 intervals, said ears being parallel with the side faces of the head 21. Slots 28 are formed longitudinally within the sides of the head, and in each slot is loosely mounted a roller 29, so-shaped that when the inner face of said 85 roller is bearing upon a mandrel the outer face will be in a plane parallel with the side of the head.

In using the tool herein described the wheel 3 is turned so as to force the tapered portion 90 of mandrel 1 out of the head 21, and thereby permit the rollers 29 to move into the head. Said head is then inserted in the end of the tube to be expanded, so as to bring said end into contact with ring 26 and between the 95 ears 27. Handle 20 is grasped in one hand and hand-wheel 3 is turned by the other until the mandrel 1 is caused to wedge tightly be-

tween rollers 29. Lever 16 is then reciprocated backward and forward upon sleeve 10, and each forward movement of said lever will cause the pawl 17 to engage one of the teeth 5 13 and partly rotate ring 12 and the sleeve and head 21 connected thereto. This movement is continued until the rollers 29 move freely within the tube, when said rollers are pressed farther outward by again rotating 10 wheel 3 on stem 2 and drawing the mandrel 1 farther into head 21. The operation above described is then repeated until the desired expansion has been produced, after which the tool can be quickly removed by rotating 15 the wheel 3 in the opposite direction, so as to loosen the mandrel and remove the pressure upon the rollers 29. The balls 11, interposed between flange 8 and sleeve 21, form a practically frictionless end bearing for the head 21.

20 It will be seen that the tool when constructed as shown and described can be readily assembled or taken apart and forms a durable and compact device.

In the foregoing description I have shown 25 the preferred form of my invention; but I do not limit myself thereto, as I am aware that modifications may be made therein without departing from the spirit or sacrificing any of the advantages thereof, and I therefore reserve the right to make such changes as fairly fall within the scope of my invention.

Having thus described the invention, what is claimed as new is—

1. In a tool of the character described, the 35 combination with a tapered mandrel having a threaded stem projecting therefrom; of a core loosely mounted upon the mandrel, a hand-wheel loosely mounted upon and engaging the core and stem, a ratchet inclosing and 40 revolvable upon the core, a head movable with the ratchet, means for rotating the head and ratchet, rollers loosely mounted in the head and bearing on the mandrel, and a centering-ring loosely mounted upon the head.
- 45 2. In a tool of the character described, the combination with a tapered mandrel having a threaded stem projecting therefrom; of a core loosely mounted upon the mandrel, a head loosely mounted upon the core at one end, a 50 hand-wheel loosely mounted upon the other end of the core and engaging the stem, rollers loosely mounted within the head and normally bearing upon the mandrel, a ring in-

closing and loosely mounted on the head, lugs projecting from the ring, and means for rotating the head upon the core and mandrel. 55

3. In a tool of the character described, the combination with a tapered mandrel having a threaded stem projecting therefrom; of a core loosely mounted upon the mandrel, a handle 60 extending therefrom, a mandrel-adjusting device loosely mounted upon the core and engaging the stem, a head revolubly mounted on the core, rollers loosely mounted within the head, a toothed ring connected to and 65 revoluble with the head, a lever, and a pawl pivoted to the lever and normally engaging the ring.

4. In a tool of the character described, the combination with a tapered mandrel having a 70 threaded stem; of a core mounted upon the mandrel, a handle secured thereto and extending therefrom, a mandrel-adjusting device engaging the stem and connected to the core, a handle secured to and extending from the core, 75 a sleeve loosely mounted upon the core, a toothed ring secured thereto, a lever revolubly mounted on the sleeve, a pawl connected to the lever and normally engaging the ring, a head secured to the sleeve and revoluble 80 therewith, and rollers loosely mounted within the head and normally bearing upon the mandrel.

5. In a tool of the character described, the combination with a tapered mandrel having a 85 threaded stem; of a core inclosing the mandrel, a mandrel-adjusting device engaging the stem and revolubly mounted upon the core, a handle secured to and extending from the core, a sleeve revolubly mounted on the core, balls 90 interposed between the sleeve and core to form an end bearing, a toothed ring secured to the sleeve, a lever revolubly mounted upon the sleeve, a pawl pivoted to the lever and normally engaging the ring, a head secured 95 to the sleeve, rollers loosely mounted therein and normally bearing upon the mandrel, a ring revolubly mounted on the head, and pins extending therefrom.

In testimony whereof I affix my signature in 100 presence of two witnesses.

JAMES J. BYERS.
